W. C. ACHTERKIRCH.
BULLETIN OR NOTICE BOARD.
APPLICATION FILED JULY 18, 1917.

1,252,640.

Patented Jan. 8, 1918.

UNITED STATES PATENT OFFICE.

WILLIAM C. ACHTERKIRCH, OF OGILVIE, MINNESOTA.

BULLETIN OR NOTICE BOARD.

1,252,640.

Specification of Letters Patent.

Patented Jan. 8, 1918.

Application filed July 18, 1917. Serial No. 181,314.

To all whom it may concern:

Be it known that I, WILLIAM C. ACHTERKIRCH, a citizen of the United States, residing at Ogilvie, in the county of Kanabec 5 and State of Minnesota, have invented certain new and useful Improvements in Bulletin or Notice Boards, of which the following is a specification, reference being had to the accompanying drawings.

10 This invention relates to display devices, and particularly to a board for supporting notices or bulletins.

The general object of the invention is to provide a bulletin supporting board and in 15 connection therewith means whereby bulletins may be held to the board, without the use of tacks, paste, or other like attaching means.

A further object is to provide a bulletin 20 board constructed of sheet metal so designed that the bulletin board may be pressed out of the sheet metal and in this connection to provide a bulletin board having a hood which will extend over the notices or bulletins 25 on the board.

A further object is to provide a construction which is very light and yet strong, and in which the bulletins or notices shall be firmly locked to the board.

30 Other objects will appear in the course of the following description.

My invention is illustrated in the accompanying drawings, wherein:—

Figure 1 is a perspective view of a bulletin board constructed in accordance with 35 my invention;

Fig. 2 is a section on the line 2—2 of Fig. 1;

Fig. 3 is a fragmentary section on the 40 line 3—3 of Fig. 4;

Fig. 4 is a fragmentary section on the line 4—4 of Fig. 1; and

Fig. 5 is a fragmentary transverse section on the line 5—5 of Fig. 1.

45 Referring to these drawings, 10 designates the bulletin board proper, which is made of sheet metal and is preferably made of sheet metal of about No. 20 gage. The sheet metal is first cut to the proper shape 50 and then stamped or soldered or welded at the joints. As illustrated the board is rectangular in form and formed to provide a hood 11 projecting upward and outward to any desired degree, the metal of the board 55 being stamped outward at the sides to form

the side flanges 12 and then bent inward and rearward again as at 13 beyond the inner face of the board. At its lower end the sheet metal of the board is folded upon itself and then rearward as at 14 to form a 60 flange disposed above the lower end of the board and at the top of the board there is a like flange 15.

The end walls or flanges 12 at their upper forwardly enlarged ends are formed with 65 sockets 16 which are pressed out of the sheet metal and disposed in these sockets is the transversely extending rod 17, which is disposed adjacent the face of the board and well beneath the hood 11. 70

The face of the board 10 is formed with a plurality of vertically extending grooves 18, these grooves being pressed out of the sheet metal and extending nearly the entire length of the board. Mounted upon the rod 17 are 75 a plurality of clamps 19. These clamps are slightly curved for their entire length and are formed of resilient metal. Preferably the inner face of each clamp is formed with a V-shaped rib 20. This V-shaped rib is 80 notched at intervals as at 21 so that the V-shaped rib will not interfere with the resilience of the strip forming the clamp 19.

Each of these clamping members 19 at its upper end is formed with a bead 22 which 85 loosely embraces the rod 17 so that the clamping members may be slid along the rod, if desired, and for a purpose which will be later stated. At their lower ends, each clamping member is enlarged and rotatably 90 mounted in this enlargement is a stud 23 having at its outer end a knob 24 whereby the stud may be rotated and having at its inner end a radially projecting lug 25 adapted to engage behind the lower margin of the 95 sheet metal bulletin board. It will be seen that when so engaged the resilience of the clamping members 19 will urge the clamping members outward so that the lug 25 will frictionally engage with the bulletin board 100 so that the stud 25 cannot be accidentally rotated. A slight depression may be made in the margin of the board with which the lug 25 could engage to prevent the accidental rotation of the stud. 105

There may be any number of grooves 18 on the face of the bulletin board. I have shown three grooves adjacent the outer margins of the board and two pairs of grooves adjacent the middle of the board, but I do not wish 110

to be limited to this. By providing a plurality of these grooves and mounting the clamping members for longitudinal movement along the rods, it is obvious that bulletins of various size may be readily clamped in position upon the board, and it will also be seen that when these bulletins are in place upon the board and engaged by the clamping members, the lateral margins of the members will be forced into the grooves and be interlocked with the bulletin board by the clamping members and the grooves.

For the purpose of mounting the bulletin board upon a standard 26, which standard I have illustrated as a metallic column, I provide the clamps 27 which are bolted or riveted to the flanges 14 and 15. I do not wish to limit myself to this means for supporting the bulletin board, however, as other means may be used. Where large bulletin boards are used, it is obvious that a plurality of columns may be used for supporting the board. It will also be obvious that my bulletin board may be modified in many ways without departing from the spirit of the invention.

Having thus described my invention, what I claim is:—

1. A bulletin board having vertically extending grooves in its face, clamping members pivotally mounted upon the board and adjustable transversely thereof and formed to engage in said grooves, and means for locking the clamping members in clamping position.

2. A bulletin board having a series of vertically extending grooves across its face, a rod extending transversely of the board, clamping members pivotally mounted upon the rod and adapted to engage in said grooves, and means carried on the clamping members and engageable with the board for holding the clamping members against the face of the board and in clamping position.

3. A bulletin board having a plurality of vertically disposed grooves in its face, a plurality of pivoted clamping members each having a V-shaped rib on its inner face adapted to engage in the groove, the clamping members being mounted upon the board for movement transversely thereof and pivotal movement in a plane at right angles to the face of the board, and means for holding said clamping members in clamping position.

4. A bulletin board having a plurality of vertically disposed grooves in its face, a plurality of pivoted clamping members each having a V-shaped rib on its inner face adapted to engage in the groove, the clamping members being mounted upon the board for movement transversely thereof and pivotal movement in a plane at right angles to the face of the board, and means for holding said clamping members in clamping position.

said clamping members being resilient and longitudinally convexly curved toward the face of the board.

5. A bulletin board made of sheet metal formed to provide a hood and outwardly projecting side flanges, a rod mounted beneath the hood and extending transversely across the board and supported by said side flanges, the face of the board being formed with a plurality of stamped vertically disposed grooves, clamping members having beads at their upper ends pivotally and slidably engaging said rod, the clamping members being curved outward and downward, the lower ends of the clamping members having means for engaging the lower margin of the board to hold them in clamping position against the face of the board.

6. A bulletin board made of sheet metal formed to provide a hood and outwardly projecting side flanges, a rod mounted beneath the hood and extending transversely across the board and supported by said side flanges, the face of the board being formed with a plurality of stamped vertically disposed grooves, clamping members having beads at their upper ends pivotally and slidably engaging said rod, the clamping members being curved outward and downward, the lower ends of the clamping members having means for engaging the lower margin of the board to hold them in clamping position against the face of the board, said means comprising a rotatable stud having a knob at one end and a lug on the inner end engaging behind the lower margin of the board.

7. A bulletin board formed of sheet metal and shaped to provide a forwardly projecting hood at the upper edge of the board and a rearwardly projecting flange and a rearwardly projecting flange at the lower end of the board, the sides of the bulletin board being outwardly bent and then rebent to extend rearward to form outwardly directed side flanges, a rod supported in the upper ends of said side flanges beneath the hood, and clamping members each rotatably mounted at its upper end upon the rod and slidably engaged therewith, said members being resilient and outwardly and downwardly curved, and means on the lower edge of said members for engaging the lower margin of the bulletin board to hold the clamping members in clamping position.

8. A bulletin board formed of sheet metal and shaped to provide a forwardly projecting hood at the upper edge of the board and a rearwardly projecting flange and a rearwardly projecting flange at the lower end of the board, the sides of the bulletin board being outwardly bent and then rebent to extend rearward to form outwardly directed side flanges, a rod supported in the upper ends of said side flanges beneath the hood,

and clamping members each rotatably mounted at its upper end upon the rod and slidably engaged therewith, said members being resilient and outwardly and downwardly curved, and means on the lower edge of said members for engaging the lower margin of the bulletin board to hold the clamping members in clamping position, and column clamping devices mounted upon the upper and lower flanges of the bulletin board.

9. A bulletin board formed of sheet metal and shaped to provide a forwardly projecting hood at the upper edge of the board and a rearwardly projecting flange and a rearwardly projecting flange at the lower end of the board, the sides of the bulletin board being outwardly bent and then rebent to extend rearward to form outwardly directed side flanges, a rod supported in the upper ends of said side flanges beneath the hood, and clamping members each rotatably

mounted at its upper end upon the rod and slidably engaged therewith, said members being resilient and outwardly and downwardly curved, and means on the lower edge of said members for engaging the lower margin of the bulletin board to hold the clamping members in clamping position, the sheet metal bulletin board being formed with a plurality of vertically extending V-shaped grooves, and each clamping member on its inner face being formed with a V-shaped rib engageable in the groove, the ribs being notched at intervals to permit the clamping member to normally curve outward and downward. 25 30 35

In testimony whereof I hereunto affix my signature in the presence of two witnesses.

WILLIAM ACHTERKIRCH.
